FIGURE 3

UNITED STATES PATENT OFFICE.

CARL BERGMAN, OF BERGENFIELD, NEW JERSEY.

TRANSFORMER.

Application filed April 12, 1924. Serial No. 706,016.

My invention relates to transformers, my particular purpose being to produce a small, neat and compact transformer suitable for office use, and provided with means for connecting it with leads from street mains, the device having a number of advantages and being adapted for energizing small appliances such as electric cauteries and miniature electric lamps as commonly used by 10 surgeons and dentists.

Reference is made to the accompanying drawing forming a part of this specification and in which like reference characters indicate like parts throughout the several 15 figures.

Figure 1 is a plan view of my improved transformer.

Figure 2 is a cross section through the same, substantially upon the line 2—2 of 20 Figure 1, looking in the direction indicated by the arrows.

Figure 3 is a fragmentary view, partly a plan and partly a section, showing various details of the transformer.

Figure 4 is a section on the line 4—4 of Figure 3, looking in the direction indicated by the arrows.

Figure 5 is a plan view of a portion of the laminated core of the transformer.

Figure 6 is a diagram of the wiring.

Figure 7 is a fragmentary section showing for certain parts a form differing slightly from the one appearing in Figures 1 to 5 inclusive.

A casing wall 8, having a general annular form, encloses most of the parts.

Detachably engaging the casing wall 8 is a casing head 9, having generally the form of a disk, and serving as a base for 40 the apparatus. The casing head 9 is provided with a raised head 10 integral with it.

Spacing posts 11 are connected with the bead 10 and extend upwardly therefrom, and support various parts, as hereinafter 45 more fully described. Screws 13, 14, connected with the spacing posts hold these posts in position.

Another casing head is shown at 15, and engages the casing wall 8. The spacing posts 50 11 are connected with this casing head.

A laminated core 16, made up of stampings of iron or steel and having a general annular form, serves as the transformer core. This core carries three supporting 55 pins 17, made of insulating material and

each insert endwise into the core as indicated in Figures 4 and 5. These supporting pins, each provided with a hole 17^a as indicated in Figure 5, are mounted upon the spacing posts 11 and thus supported 60 by the casing head 15, so that the core 16 and parts carried thereby are insulated from this casing head and from other metallic parts.

A jacket 18 of insulating material encompasses the laminated core 16, and thoroughly insulates it throughout its entire extent. Wound upon the jacket 18 is the primary winding 19. The primary winding extends throughout the entire length of the 70 core 16, and is preferably made of fine wire. This enables it to be safely connected with street mains, or with taps leading therefrom—or in other words, to be used with ordinary commercial currents. 75

The ends of the primary winding 19 are shown in Figure 3 at 20, 21, and are secured to plug connections 22, 23, carried by a block 24 of insulating material. By aid of the plug connections, the primary winding 80 can be instantly connected with or disconnected from any available source of alternating current.

A jacket 25 of insulating material covers and also conceals the primary winding 19. 85

Coiled upon the jacket 25 of insulating material, and consequently wound around the core 16 and primary winding 19, are two secondary windings 26, 27, disposed upon opposite sides of the core, as may be understood from Figure 3.

The secondary winding 26 comprises a few turns of coarse wire, and is thus adapted to supply currents of low voltage, suitable for heating an electric cautery. The winding 27 is made of wire somewhat finer than the secondary winding 26, and comprises a greater number of turns. The secondary winding 27 is adapted to supply currents suitable for energizing a miniature lamp. 100

For convenience I designate the secondary winding 26 as a heating coil, and the secondary winding 27 as a lighting coil.

Four binding posts 28, 29, 31, 32, are carried by the casing head 15. The binding posts 29 and 32 are mounted directly upon this casing head, and in direct metallic communication therewith. The binding post 28 is insulated from the casing head and is connected with the adjacent end of the second- 110

ary winding 26. The opposite end of this winding is dead-ended at 30, as indicated in the figure last mentioned.

5 A vertical shaft 34 extends through a hole in the casing head 15, and is thus journaled upon the casing head. The shaft 34 carries a knob 35 to be grasped by hand and used for turning the shaft within predetermined limits, as hereinafter described.

10 The shaft 34 carries at its bottom end a contact spring 36, preferably built up of strips of copper and thus having a laminated structure. This contact spring presses upon the adjacent convolutions of the secondary winding 26, and is provided with a stubby downturned end portion 37, which makes at all times a sliding engagement with the casing head. By this arrangement the contact spring 36 is always in metallic communication 15 with the casing head 9, and is grounded if the casing is grounded.

15 Mounted rigidly upon the shaft 34 is a stop arm 38, having the form indicated more particularly in Figure 1, and serving to some 20 extent as a pointer. Since the contact spring 36 and the knob 35 are each mounted rigidly upon the shaft 34, it follows that these parts move together and practically as a unit, so that whenever the knob is turned by 25 hand to any extent in either direction the contact spring and the stop arm 38 must each be turned correspondingly, to the same extent and in the same direction.

30 Closely associated with the stop arm 38, 35 the casing head 9 is provided with a scale and with numerals spaced apart and serving as graduations. This scale as a whole is indicated in Figure 1 by the numeral 39, and is used in connection with the measurement 40 and control of currents used for heating a cautery, as hereinafter more fully described.

45 Mounted adjacent the scale 39 is a rib 40 having a general arcuate form, and detachably fitted upon it is a clamping block 41, carrying a set screw 41^a. The operator by turning this set screw in one direction can tighten the clamping block 41 upon the rib 40, and by turning the set screw in the opposite direction can loosen the clamping 50 block. Thus the clamping block can be loosened and moved along the rib 40 in either direction and to any extent permitted by the length of this rib, and then tightened. A pair of stop pins 38^a, 38^b are mounted upon 55 the casing head 15, and are disposed in proximity to the ends of the rib 40. The stop arm 38 can travel from one of these stop pins to the other, except when the clamping block 41 occupies a position somewhere on the rib 40 and intermediate the stop pins. In this event the stop arm 38 is free to move from the stop pin 38^a to clamping block 41. With the stop arm 38 occupying the position indicated for it in 60 Figure 4, it can move anywhere between 0

and 4, and with the stop arm resting against the clamping block in the position here indicated, the cautery will receive 4 amperes or other units of current.

65 Another stop arm 42, somewhat similar to the stop arm 38, is journaled upon the shaft 34, and may be moved relatively to the same by hand. For this purpose the stop arm 42 carries a thumb piece 43. The operator by grasping the thumb piece 43 can 70 move the stop arm 42 back and forth. A pair of stop pins 44 and 45 are mounted upon the casing head 15, and define the extremes of travel possible for the stop arm 42. Associated with this stop arm is a scale 75 46, provided in this instance with numerals from 0 to 5, and used for measuring and controlling currents used in connection with an electric lamp, as hereinafter more fully described. Mounted upon the casing head 80 15 and disposed adjacent the scale 46 is a rib 47 of arcuate form. The scale 46 and rib 47 are in structure and action very much like the scale 39 and rib 40 above described. A clamping block 48, provided with a set 85 screw 49, is detachably and adjustably mounted upon the rib 47, and is used in connection with the scale 46 in the manner above described in reference to the clamping block 41, associated with the scale 39. 90 The operator by shifting the clamping block 48 into different positions along the rib 47 can limit the travel allowed for the stop arm 42, and in doing this can regulate the 95 amount of current controlled by the position of the stop arm 42. With the apparatus in the condition indicated in Figure 1, the maximum current permitted by the position of the stop arm 42 is three amperes, or other units of measurement contemplated by the 100 numerals of the scale 46.

105 Instead of the ribs 40 and 47, provided with clamping blocks 41 and 48, I may use as an equivalent the structure shown in Figure 7. Here the casing head appears at 50 and carries a rib 51 provided with a channel 52, and merging into this channel is a slot 53. A bolt 54 extends through the slot 53, and is provided with a head 55 which fits loosely within the channel. A washer 56 110 encircles the bolt, and rests upon the rib 51. A set screw 57 engages the bolt, and is used for tightening and loosening the same. The operator by turning the set screw 57 and loosening the bolt can slide the bolt along the rib, and then by turning the set screw in the opposite direction can tighten the bolt. The bolt with its washer 56 serves the same purpose as either of the clamping 115 blocks 41, 48. A contact spring 58 is connected with the stop arm 42 by means of a hub 34^a through which the shaft 34 extends. Thus the contact spring 58 turns with the stop arm 42, and since the hub 34^a is loose 120 relatively to the shaft, the movement of the 125 130

stop arm 42 and contact spring 58, as a unit, is independent of movements of the shaft 34 and the various parts carried thereby.

By the adjustment of the stop arm 42 relative to the scale 46 as above described, the current flowing through the secondary winding 27 may be varied.

I will now explain the diagram shown in Figure 6.

10 By means of the plug connections 22, 23, above described, the primary winding 19 is connected directly with a pair of feed wires 59, and thus supplied with alternating current, and energized accordingly. A pair of 15 conductors 60 and 61, such as conducting coils or wires, are connected with the binding posts 31, 32, and lead therefrom to an incandescent lamp 62 of the type used in surgery.

20 Similarly a pair of conductors 63 and 64, are connected with the binding posts 28, 29, and lead therefrom to a cautery, indicated diagrammatically at 65.

The lamp circuit is shown as grounded 25 at 66, and the cautery circuit at 67. These two grounds are very conveniently made by simply grounding the casing, in any convenient manner.

30 In my device there is considerable economy of construction due to the arrangement just described. That is to say, there is a saving due to the fact that no effort whatever is made to insulate the shaft 34 or any of the parts carried by it, since the shaft 34 and all of its various metallic connections may be considered as grounded through the casing.

35 The only insulation required, therefore, is for the various windings, and the very 40 simple electrical connections absolutely necessary for conveying the currents into and out of these windings.

I do not limit myself to the particular mechanism shown, as variations may be 45 made therein without departing from my invention, the scope of which is commensurate with my claims.

Having thus described my invention what 50 I claim as new and desire to secure by Letters Patent is as follows:

55 1. A device of the character described comprising a casing provided with a pair of casing heads, a plurality of posts each extending through said casing and connected with both of said casing heads, a transformer core having a general annular form and provided with openings, members of insulating material disposed within said openings and extending therefrom, said members 60 of insulating material being connected with said posts for the purpose of supporting said core by aid thereof, transformer windings mounted upon said core and insulated therefrom, and mechanism mounted upon one of 65 said casing heads and connected with said

transformer windings for enabling the operator to control said transformer windings.

2. In a device of the character described the combination of a casing, a stop arm journaled upon said casing and movable angularly in relation thereto, means controllable by the operator for adjusting the limits of travel of said stop arm, a transformer mounted within said casing, movable contact mechanism connected with said transformer for the purpose of controlling electric currents generated thereby, said movable contact mechanism being connected with said stop arm and controllable by the different positions into which said stop arm is moved, and means for energizing said transformer.

3. In a device of the character described the combination of a casing provided with a casing head, a rib mounted upon said casing head, a clamping block connected with said rib and adjustable bodily into different positions along the same, a stop arm journaled upon said casing head and movable into different positions relatively to said rib, said clamping block serving as a stop for limiting the travel of said stop arm, a transformer mounted within said casing, movable contact mechanism connected with said transformer for the purpose of controlling currents generated thereby, said movable contact mechanism being connected with said stop arm and controllable by the travel thereof relatively to said clamping block, and means for energizing said transformer.

4. In a device of the character described the combination of a casing provided with a casing head, a plurality of ribs carried by said casing head, each of said ribs having an arcuate form, a pair of clamping blocks, one for each rib, each clamping block being connected with the rib with which it is associated and adjustable bodily into different positions along the same, a plurality of stop arms journaled relatively to said casing head and movable into different positions relatively to said ribs, a clamping block connected with each rib for limiting the travel of one of said stop arms relatively thereto, a transformer mounted within said casing, a plurality of movable contact mechanisms connected with said transformer for the purpose of controlling currents generated thereby, connections from said movable contact mechanisms to said stop arms for the purpose of enabling said movable contact mechanisms to be limited by movements of said stop arms, and means for energizing said transformer.

5. In a device of the character described the combination of a casing provided with a casing head, a stop arm journaled upon said casing head and movable angularly, means controllable by the operator for adjusting the limits of travel of said stop arm,

- a transformer mounted within said casing, movable contact mechanism connected with said transformer for the purpose of controlling electric currents generated thereby, said movable contact mechanism being connected with said stop arm and controllable by the different positions into which said stop arm is moved, and means for energizing said transformer.
6. In a device of the character described the combination of a casing provided with a casing head, a pair of stop arms disposed adjacent said casing head and journaled to turn upon a common axial center, said stop arms being movable independently of each other, means controllable by the operator for limiting to any desired extent the travel of the respective stop arms, a transformer mounted within said casing, a pair of movable contact mechanisms connected with said transformer for controlling different sets of electric currents generated thereby, connections from said contact mechanisms to said stop arms for the purpose of enabling each of the stop arms to actuate one of the contact mechanisms, and means for energizing said transformer.
